UNITED STATES PATENT OFFICE

PETER N. LANDINE, OF MILFORD, CONNECTICUT

SECTIONAL SCREEN

Application filed October 24, 1929. Serial No. 401,988.

This invention relates to screens and particularly to an improved form of frame for screens having a plurality of hinged sections.

An object of the present invention is to improve the construction of frames for the screen sections so that there will be no tendency to warp the sections when they are being put together.

Another object of the invention is to improve the corners of the screen frames and the joints connecting the sections of the screen together so that they may have free pivotal movement relative to each other.

A feature which is advantageous is that the hinge connections between the adjacent sections of the screen comprises square rods extending within the tubular frame members of the sections, one of these rods being provided in each portion of a frame to be hinged, these rods at their upper and lower ends being extended and threaded into nuts housed within strap or link members connecting the sections of the screen together.

Another feature of importance is that the openings in the corner reinforcing members and in the tubular members of the frame are square and closely fit the rods passing through them so that when the nuts at opposite ends of the rods are tightened there is no tendency to twist the rods and warp the frames.

With these and other objects in view my invention includes the features of construction and operation set forth in the following specification and illustrated in the accompanying drawing.

In the accompanying drawing annexed hereto and forming a part of this specification I have shown my invention embodied in a fireplace screen comprising three hinged sections, but it will be understood that the invention can be otherwise embodied and that the drawing is not to be construed as defining or limiting the scope of the invention, the claims appended to this specification being relied upon for that purpose.

In the drawing—

Fig. 1 is a front elevation of a complete screen, the sections thereof being shown in extended position;

Fig. 2 is a fragmentary view of the screen, in elevation, showing a joint and adjacent portion of the screen upon an enlarged scale;

Fig. 3 is a detail plan view, showing the joint between adjacent sections of the screen; 55

Fig. 4 is a sectional view taken upon the plane of line 4—4, in Fig. 1.

In the above mentioned drawing I have shown but one embodiment of the invention 60 which is now deemed preferable, but it is to be understood that changes and modifications may be made within the scope of the appended claims without departing from the spirit of the invention. 65

Referring more in detail to the figures of the drawing I provide a screen preferably having a plurality of connected sections 10, three being shown in the present embodiment. Each of these sections 10 comprises a frame 70 11 made up of lengths of hollow material each length being slotted and slightly opened or cut along their length as shown in Fig. 4. Within this elongated and narrow slot is inserted the wire mesh material forming the 75 body or panel of the screen so that the raw edges of the mesh material may be secured and hidden within the frame of tubing 11. The corners of the frame 11 are mitered and brazed or otherwise fastened securely to 80 together after the wire mesh material has been positioned.

At each of the corners of each of the frames 11 I provide a special corner reinforcing member or elbow 12 of angular form and extending partially around the tubing forming the frame 11. These elbows or reinforcing members 12 are shown clearly in Figs. 2 and 4. 85

The corner members or elbows 12 may be brazed or otherwise fastened to the inner 90 surface of the tubing 11 adjacent the corners. Extending through the tubing 11 in that portion of a section 10 adjacent another is a noncircular and preferably square rod 13 which passes through closely fitting openings formed in the elbow or reinforcing members 12 and tubing 11. This constitutes one means for permanently preventing both ends of each rod from turning in its respective frame end. These rods 13 as shown in Fig. 2 100

extend above and below the outside surfaces of the tubing 11 of the frames 10 and have their extended portions suitably threaded. Supported on these threaded extensions of the 5 square rods 13 are nuts 14 housed within link members 15 by means of which the adjacent sections 10 are connected together. The nuts 14 are threaded onto the rods 13 within counterboard recesses in the links 15 so that 10 they bear firmly against the unthreaded ends of the rods 13. The sections, therefore, are connected for free pivotal movement by movement of the link member 15 on the nuts 14. As the ends of the rods 13 pass through 15 closely fitting openings in the elbows 12 and tubing 11 adjacent the threaded portions of the rods 13 these rods 13 are not twisted when the nuts 14 are tightened. By this construction the screen sections 10 effectively resist 20 such strains as would cause warping or other distortion when opened and closed by the user.

The upper and lower ends of the rods 13 may have identical constructions so far as the 25 links 15 and nuts 14 are concerned. The top ends, however, may have suitable balls 16, or other ornamentation, applied to them as shown in section in Fig. 2.

I claim:

- 30 1. A folding screen comprising a plurality of sections, each section including a wire mesh panel, a frame surrounding and supporting said panel and formed of hollow metal pieces rigidly connected to each other at the corners of said frame, each of said pieces having a longitudinal slit at the inside of the frame to receive the adjacent edge of the mesh panel, a rod extending entirely through and beyond the ends of one of the hollow 35 pieces to form link supports to connect one screen section to another, and means to permanently prevent both ends of said rod from turning in both ends of the hollow piece through which it passes.
- 40 2. A folding screen comprising a plurality of sections, each section including a wire mesh panel, a frame surrounding and supporting said panel and formed of hollow metal pieces rigidly connected to each other at the corners of said frame, each of said pieces having a longitudinal slit at the inside of the frame to receive the adjacent edge of the mesh panel, a rod extending entirely through and beyond the ends of one of the hollow 45 pieces to form link supports to connect one screen section to another, and means to permanently prevent both ends of said rod from turning in both ends of the hollow piece through which it passes, the extreme ends 50 of said rod being screw threaded, and nuts for said threaded ends to hold connector links.

PETER N. LANDINE.
